TENNIS RACKET PRESS COVER

Filed Feb. 5, 1962

A diagram showing a strip of material, possibly a polymer or composite, with various features labeled. The strip is oriented horizontally. At the top, there is a layer with vertical striations. Several labels point to specific features: '10' points to a vertical striation on the left; '5' points to a vertical striation in the center; '13' points to a vertical striation on the right; '15' points to a vertical striation on the far right; '20' points to a vertical striation near the bottom right; '21' points to a vertical striation near the bottom left; '6' points to the left edge of the strip; and '12' points to a vertical striation near the bottom center. The labels are in a black font, and the numbers are placed near the corresponding features.

TENNIS RACKET PRESS COVER
Lucille F. Baukney, 1520 NE. 40th Court,
Fort Lauderdale, Fla.
Filed Feb. 5, 1962, Ser. No. 170,928
5 Claims. (Cl. 273—74)

This invention relates to a combined cover and press for tennis rackets or similar articles of such nature as will protect the head of a tennis racket against the elements and to also maintain the frame of the tennis racket against warping.

The invention contemplates a molded plastic cover that is shaped in top plan to conform to the general oval shape of the head of a tennis racket and with the cover being formed of relatively stiff plastic that will avoid flexing and that will maintain the head of the tennis racket in a normal flat condition. The cover embodies upper and lower flat walls that are partially connected by a connecting vertical wall and with a part of the vertical wall being omitted to form an opening for the insertion of the head of the racket and with a slide device that is adapted to close the opening after the racket has been inserted.

Novel features of construction and operation of the device will be more clearly apparent during the course of the following description, reference being had to the accompanying drawings wherein has been illustrated a preferred form of the invention and wherein like characters of reference are employed to denote like parts throughout the several figures.

In the drawings:

FIGURE 1 is a top plan view of the cover and associated parts illustrating the manner of inserting the head of the tennis racket therein,

FIGURE 2 is an edge view of the cover with a closure slide in the open position,

FIGURE 3 is an end view of the cover taken from the left end of the illustration in FIGURE 1,

FIGURE 4 is a transverse section taken substantially on line 4—4 of FIGURE 1,

FIGURE 5 is a longitudinal section taken substantially on line 5—5 of FIGURE 1,

FIGURE 6 is a horizontal section taken substantially on line 6—6 of FIGURE 2 with the tennis racket being shown in dotted lines,

FIGURE 7 is a fragmentary section through one edge of the cover with a closure slide omitted, and

FIGURE 8 is a fragmentary perspective view of a slide device adapted to cover and uncover the opening of the device.

Referring specifically to the drawings, there has been illustrated a tennis racket cover and press of generally oval shape in top plan, shown as a whole by the numeral 5. The cover 5 embodies flat parallel upper and lower plates 6, that are connected for the major circumference of the device by a wall 7. The cover terminates at one end in a reduced throat extension 8. The wall 7 extends from one side of the throat 8 around the circumference of the cover and terminates at a point 9, providing a relatively large opening 10 for the insertion of the head portion 11 of a tennis racket of conventional construction, having the usual handle 12. The plates 6 and the walls 7 are integrally molded to form a relatively stiff cover for the tennis racket head 11 and with the handle 12 being disposed within the throat 8 after the racket has been fully inserted into the cover. The major portion of the device, conforming to the curvature of the cover and the opening 10 is provided with upper and lower integral flanges 13, that project above the outer surfaces of the cover 6 a predetermined distance and with the flanges 13 upon the inner side having diagonal grooves 14. The flanges 13 may be partial, as indicated in FIGURE 1 or,

2

the flanges may be co-extensive with the cover to terminate at the ends of the throat 8. However, the flanges have been illustrated as being of such length as to provide a guide for a cover device, to be described.

5 Adapted to cover and uncover the opening 10, is a relatively flexible cover device, illustrated as a whole by the numeral 15. The cover device 15 may be formed of any desirable material and of course may be molded of plastic or possibly metal. The cover device 15 as more clearly illustrated in FIGURE 8 embodies a generally U-shaped member having a closure wall 16 and with the wall 16 at its upper and lower edges being flanged at 17. The flanges 17 terminate in inwardly directed walls 18, that have their terminal edges angled inwardly to form guide tongues 19. The angularity of the guide tongues 19 are identical with the angularity of the grooves 14 of the flanges 13 and the spacing of the flanges 17 is such as to have a frictional guiding engagement upon the marginal portions of the flanges 13. The cover 15 at one or both 10 ends is provided with an actuating lip 20 whereby the cover may be manually shifted to and from a covering relation with respect to the opening 10. The cover 15, when formed of plastic will obviously be flexible to such an extent that the cover may be caused to traverse flanges 13 to a position where the opening 10 is fully exposed for either the insertion or removal of the tennis racket. Where the flanges 13 are co-extensive with the plates 6, the additional extension will obviously constitute more of an ornamental appearance. The neck portion 8 may be 15 provided adjacent its open end with a band or U-shape and preferably soft rubber seal, indicated at 21.

In the use of the device, when a tennis racket is adapted to be covered, the slide 15 is shiftable along the flanges 13 by the lip 20, to the point closely adjacent to the end 20 portion 9 of the wall 7. The tennis racket is then inserted at an angle through an opening 10 to its full depth into the cover or, where the head of the tennis racket has abutting engagement with the inner side of the wall 7, at which time the handle 12 of the tennis racket is swung laterally to cause the neck portion between the handle 12 and the head 11 to be fully engaged into the throat 8. The cover 15 is then shifted along the flanges 13 to fully cover the opening 10 and to terminate at the end portion of the throat 8. The engagement of the tongues 19 into 25 the grooves 14, form a very definite tie between the upper and lower walls 6 that will prevent any tendency for the walls 6 in the area of the opening 10 to flex away from the racket head 11. The inner dimensions of the cover are adapted to conform closely to the head 11 of the racket so that the plates 6 will have a relatively snug engagement with the upper and lower sides of the frame constituting the head 11 and, since the cover is formed of relatively stiff plastic material, the racket will be securely maintained against any tendency to twist during storage 30 or due to weather conditions and the use of the seal 21 avoids the possible entry of moisture into the cover that possibly might affect the cords of the racket head 11. The cover 15 has a relatively snug engagement with the flanges 13 and such also will effectively seal the opening 10.

It will be apparent from the foregoing that a very novel type of molded plastic and relatively rigid cover has been provided for tennis rackets, the device may be molded from any suitable reinforced plastic such as the well known standard epoxy-glass laminate and while the device has been indicated as being formed of such plastic, the device could obviously be formed of light weight metal, such as aluminum. The device is cheap to manufacture, is strong, durable and forms a most desirable combined cover and press for the head portion of conventional tennis rackets.

It is to be understood that the invention is not limited

to the precise construction shown, but that changes are contemplated as readily fall within the spirit of the invention as shall be determined by the scope of the subjoined claims.

Having described my invention what I claim as new and desire to secure by Letters Patent is:

1. A combined tennis racket cover and frame press that comprises a molded plastic housing of generally oval shape in top plan and that consists of a pair of flat plate sections that are parallel and spaced apart in accordance with the thickness of the tennis racket head, the plates around their major circumference being rigidly connected together by an integral marginal wall, the housing at one end being provided with a reduced throat extension that receives an adjacent portion of a handle for the racket head, the throat being open at its end and one side, the marginal wall at one side of the housing being omitted to form an access opening whereby the head of the racket may be inserted into a chamber that is formed by the plates and the marginal wall, a flexible slide that is slidably connected to the plates whereby to cover and uncover the access opening, the slide when in a covering position being co-extensive with the access opening of the one side and the side opening of the throat.

2. The structure in accordance with claim 1, wherein the plates at their marginal edge are provided with integral grooved flanges, the said slide upon its marginal edges having flanges that traverse the grooves, the flanges of the slide providing an interlocking engagement with the grooves of the first named flanges whereby to hold the plates against separation in the area of the access opening.

3. The structure according to claim 2, wherein the flanges of the plates are outwardly extending and with the grooves of the flanges being formed upon the inner side of the flanges and inwardly and downwardly inclined into the flanges, the flanges of the slide having a snug sliding engagement in the grooves of the first named flanges, the slide at one end being provided with a right angle lip whereby to manually actuate the slide.

4. The structure according to claim 1 wherein the throat extension is provided with a compressible seal ring for engagement with the handle of the racket whereby to effectively seal the chamber when the racket head is housed therein.

5. A molded plastic combined cover and press for tennis rackets that comprises a cover that is shaped to conform to the curvature of the head portion of a tennis racket, the cover embodying a pair of spaced apart flat parallel walls of substantially oval shape that are connected together by an integral marginal wall, the spacing of the flat parallel walls defining a chamber for the reception of the head of the racket whereby the several walls will snugly engage the opposite faces of the racket and the marginal edges of the racket head, the cover terminating at one end in a reduced throat extension adapted to embrace a portion of a tennis racket handle, the marginal wall upon one side of the cover being omitted to form an access opening whereby the head of the racket may be inserted into the cover, the access opening also extending through the throat extension and a slidable cover device for closing the access opening, the said cover being formed of relatively hard and non-flexible plastic calculated to prevent warping of the tennis racket, the slidable cover being formed of a relatively pliable plastic whereby to permit the cover to slide and conform to the marginal edges of the cover.
